(57) **CLAIM**

The ornamental design for a medical instrument, as shown and described.

DESCRIPTION

FIG. 1 is a top, front, left perspective view of a medical instrument in accordance with our design;
FIG. 2 is a top plan view thereof;
FIG. 3 is bottom plan view thereof;
FIG. 4 is a left side elevational view thereof;
FIG. 5 is a right side elevational view thereof;
FIG. 6 is a front elevational view thereof; and,
FIG. 7 is a rear elevational view thereof.

The broken lines represent portions of the medical instrument that form no part of the claimed design.
